United States Patent Office.

JAMES STORMS AND HENRY DORER, OF BUFFALO, NEW YORK.

Design No. 3,745, dated November 9, 1869.

DESIGN FOR AN ELEVATOR-BUCKET.

The Schedule referred to in these Letters Patent and making part of the same.

To all whom it may concern:

Be it known that we, JAMES STORMS and HENRY DORER, of Buffalo, in the county of Erie, and State of New York, have invented a new and useful Design for Elevator-Buckets; and we do hereby declare the following to be a clear and exact description of the nature thereof, sufficient to enable others skilled in the art to which our invention appertains, to fully understand and use the same, reference being had to the accompanying drawings, making part of this specification, in which the figure is a perspective view.

It will be seen that the back of the portion B is straight or flat, and the front elliptical, and so continues to the point where it joins the flat back. The

portion B is wider from side to side than from front to back.

Having thus described our invention,

What we claim as new, and desire to secure by Letters Patent, is—

The design for elevator-buckets, as herein represented and described.

In witness whereof, we have hereunto signed our names, in the presence of two subscribing witnesses.

JAMES STORMS.
HENRY DORER.

Witnesses:

J. R. DRAKE,
C. N. WOODWARD.
